UNITED STATES PATENT OFFICE.

CHESLEY T. SMALL, OF ST. LOUIS, MISSOURI.

CAN-SHAPING MACHINE.

Application filed January 19, 1923. Serial No. 613,635.

In the manufacture of cylindrical paper receptacles, which I have referred to for convenience throughout the specification and claims as cans, it is desirable to reduce 5 or "neck in" the ends of the can so that when the ends or caps are in position, the can will be of uniform outside diameter throughout its entire length. Although the desirability of such can construction, both 10 for convenience in applying labels and packing the can, is evident, it has not come into general use because the machines and methods heretofore in use on sheet metal cannot be successfully applied to paper cans. I 15 have found, however, that the ends of paper cans can be successfully reduced or necked in by applying to them a rolling and compressing action between an inner and an outer member both approximating to the 20 size and shape of the can and eccentrically positioned with respect to each other at the time of operation, so as to produce a planetary movement.

It is the object of the present invention 25 to produce a simple and effective machine, operating on the principle above outlined, for reducing or "necking in" the ends of paper cans.

In the accompanying drawings which illustrate a machine made in accordance with 30 my invention, Fig. 1 is a side elevation; Fig. 2 is a front view; Fig. 3 is an enlarged section taken on the line 3—3 of Fig. 2; Fig. 4 is a section taken on the line 4—4 of Fig. 35 1; Fig. 5 is an enlarged vertical section through one of the forming heads; Fig. 6 is an enlarged sectional view showing the manner of supporting the lower forming head; Fig. 7 is a section through one of the forming 40 heads and its co-operating roll carrying member, the section through the forming head being taken on the line 7—7 of Fig. 5; Fig. 8 is a view similar to Fig. 7, the section through the forming head being taken 45 on the line 8—8 of Fig. 5, and a modified form of roll carrying member being shown; Fig. 9 is a detail view showing the stop for the roll carrying member and Fig. 10 is a 50 sectional view of a can body formed by my machine with a cap applied to one end.

1 indicates a column forming the main part of the frame of the machine and terminating at its lower end in a base 2 and at its upper end in a table 3. Secured to the 55 table 3 by bolts 4 passing through slots 5 is a casting 6 forming a gear casing and

carrying a spindle 7, on which is mounted the upper forming head to be hereinafter described. The slots 5 allow of the adjustment of the casting 6 on the table 3 to align 60 the forming heads. Keyed on the shaft 7 is a sleeve 8 (Fig. 3) carrying a pair of mitre gears 9. 10 is a mitre gear mounted on a shaft 11 carrying tight and loose pulleys 12 and 13, by means of which power 65 is communicated to the machine. The sleeve 8 is provided with an annular groove engaged by a fork 14 carried on a plate 15. Carried on the plate 15 are a pair of threaded studs 16 projecting through slots 70 17 in the front of the casing 6 and engaged by nuts 18. By loosening the nuts 18 the plate 15 may be raised or lowered, carrying with it the sleeve 8 and thus bringing one or the other of the mitre gears 9 into 75 engagement with the gear 10 to drive the spindle 7 in either direction as desired.

Carried on the lower end of the spindle 7 is the upper forming head consisting essentially of a chuck 20, adapted to enter the 80 can body 21, and a surrounding annular member 22 which I have termed a crimping member. The chuck 20 has a central aperture 23 provided with a threaded portion 24 to receive a correspondingly threaded portion on the lower end of the spindle 7. The periphery of the chuck 20 is provided with an offset 25 and the member 22 with an offset 26. The larger internal diameter of the chuck 20 is somewhat less than the internal diameter of the can body 21, to be 85 operated upon, and the smaller internal diameter of the member 22 somewhat greater than the external diameter of said body so that when these parts are in concentric 90 relation, as shown in Fig. 5, the end of the can may readily be entered between them. The member 22 is provided with an inwardly projecting flange 27 overlapping a shoulder 28 on the chuck and having its inner 100 edge beveled as shown at 29. A ring 30 having a lower beveled face 31 bears on the face 29. The faces 29 and 31 are normally held in contact by springs 32 situated between the ring 30 and a backing member 33 105 screwed onto a threaded collar 34 on the chuck 20. A lock nut 35 retains the backing member 33 in position. Sliding pins 36 prevent relative rotation between the ring 30 and backing member 33. The pressure 110 of the ring 30 on the face 29 not only tends to keep the chuck 20 and member 22 in

concentric relation, but also forces the face of the flange 27 against the face of the shoulder 28 to frictionally drive the crimping member from the chuck. When, during the operation of forming the can body, the crimping member is moved into eccentric relation to the chuck, the ring 30 will be forced toward the backing member 33 and at the same time the pressure between the ring and flange will be concentrated at one point, thus tending to tip the ring out of the horizontal plane. In order that this tendency to tip the ring may not cause binding of the parts, I provide the ring with a ball race containing anti-friction balls 37 adapted to bear against the face of a bearing ring 38.

The lower forming head is a duplicate of the upper head above described and its parts are similarly numbered. The lower head has screwed into its central aperture 23 a bushing 40 (Fig. 6) adapted to receive the upper end of a shaft 41, a ball bearing 42 being interposed to allow the lower chuck to rotate on the shaft with the minimum of friction. The shaft 41 is slidably mounted in a bracket 43 on the column 1 in alignment with the spindle 7. On the shaft 41 are a pair of adjustable set collars 44 and 45 respectively. The upper collar 44 limits the upward movement of the shaft 41. Movement is imparted to the shaft through a compression spring 46 bearing at one end on the collar 45 and at the other on a sleeve 47 slidably mounted on the shaft. A pin 48, carried by the collar, is engaged by the slotted end of an arm 49 pivoted at 50 to a lug 51 on the column 1 and provided with a bifurcated rearward extension 52. The extension 52 is connected by a link 53 with an operating treadle 54 pivoted at 55 to the base 2. Projecting laterally from the extension 52 is a bar 56 carrying a set screw 57 adapted to strike against the column 1 and thus form an adjustable stop for limiting the downward movement of the lower forming head. Secured to the end of the bar 56 is a counterpoise 58 for balancing the weight of the crimping member and shaft. The counterpoise is removable so that it may be replaced by one of different weight when a crimping member of different size is used.

Pivoted to the extension 52 at 60 is a connecting rod 61 extending upwardly and passing through a lug 62 on one arm of a bell-crank lever 63 pivoted at 64 to a lug on the column 1. The rod 61 is threaded to receive a pair of jam nuts 65 forming an adjustable abutment adapted to engage the lug 62 to actuate the bell-crank lever. A link 66 connects the second arm of the bell-crank lever with a sleeve 67 adjustably mounted on a threaded rod 68 carried by a slide 69 mounted between the table 3 and casing 6. Carried on the forward end of the slide 69

is a roll casing 70. The casing 70 is preferably provided with two rolls 71, as shown in Figs. 2 and 7, but a single roll may be used as shown in Fig. 8. The object of the roll or rolls 71 is not only to move the crimping member 22 into eccentric relation to the chucks 20 (as shown in Fig. 8) but at the same time to rotate the lower chuck from the upper one, through the medium of the members 22, thus relieving the torsion on the can body which would otherwise be required to transmit all the power for driving the lower chuck. Usually the metal of the roll or rolls 71 may come directly in contact with the metal of the members 22. When, however, the power to be transmitted is considerable, it is desirable to apply, either to the members 22, or to the rolls 71, or to both, a covering of yielding material to increase the friction. In Fig. 1 I have shown such a covering in the form of rubber rings 73 applied to the crimping members 22. A coil spring 74 operates to return the roll casing 70 after it has been operated by the treadle and this return movement is limited by an adjustable stop 75 (Fig. 9) carried by the slide 69 and striking against a shoulder on the casing 6. By properly limiting the return movement of the roll holder, the rolls 71 assist the rings 30 in centering the crimping member with respect to the chucks.

The operation of my machine is briefly as follows. The machine is adjusted for the length of can body to be operated upon and power is applied through the tight pulley 12 to rotate the spindle 7. If the can body is spirally wound, the machine will be found to operate more effectively with the spindle 7 rotating in one direction than when rotating in the other, accordingly as the body is wound in a right or left hand spiral. The proper direction of rotation is secured by shifting the collar 8 to bring one or the other of the mitre gears 9 into engagement with the gear 10. One end of the can body 21 is inserted between the member 22 and chuck 20 of the lower forming head, which also serves as a can support, and the treadle 54 is depressed. Operating through the links 55 and extension 22, the treadle swings the arm 49 on its pivot to raise the shaft 41 and, consequently, the lower forming head so as to cause the upper end of the can body to enter the space between the crimping member and chuck of the upper forming head. This movement is limited by contact of the set collar 44 with the lower end of the bracket 43. Further movement of the treadle compresses the spring 46. The connecting rod 61 is drawn downwardly during the entire movement of the treadle and its jam nuts 65 are so adjusted as to come in contact with the lug 62 just at, or slightly after, the time the upward movement of the shaft 41 is arrested. Contact of the

jam nuts 65 with the lug 62 rocks the bell-crank lever 63 on its pivot, thus forcing the slide 69 and attached roll casing 70 forward to move the crimping members 22 into eccentric relation to the chucks to reduce the ends of the can body, as shown in Fig. 10, by rolling pressure between said parts. It will be noted by reference to Fig. 5 that when the backing member 33 is set up against the end of the bearing 38, as shown in this figure, there is just sufficient room between said member and the shoulder 28 to prevent binding of the crimping member. With this adjustment, the end of the can body will be turned over only sufficiently to fill the slightly rounded corner of the shoulder 28. When, however, it is desired to turn over the end of the can to greater extent, the lock nut 35 is loosened and the backing member 33 retracted a distance equal to the thickness of the can wall, after which it is secured in position by the lock nut. The end of the can may now be forced into the space between the flange 27 and shoulder 28. It will, of course, be understood that with the latter adjustment, the set collar 44 must be moved to allow the forming heads to approach each other somewhat nearer for a given length of can body than when the end of the can is not turned over.

Having fully described my invention, what I claim as new and desire to secure by Letters Patent of the United States is:

1. In a device of the class described, the combination with a pair of chucks each adapted to enter one end of a can and provided with an annular crimping member, of a roll adapted to simultaneously cooperate with both said annular members to move them laterally and to communicate motion from one to the other, and means for moving said chucks toward each other, said means also operating said roll.

2. In a device of the class described, the combination with a chuck adapted to enter

a can body, of a crimping member surrounding said chuck and provided with an overlapping flange, the inner face of said flange being inclined, a yieldingly mounted annular member provided with an inclined face bearing on the inclined face of said flange, and an adjustable backing member for said annular member forming a positive stop for the crimping member.

3. In a device of the class described, the combination with a chuck adapted to enter a can body, of a crimping member surrounding said chuck and provided with an overlapping flange, the inner face of said flange being inclined, a yieldingly mounted annular member provided with an inclined face bearing on the inclined face of said flange, and an anti-friction bearing for the inner face of said annular member.

4. In a device of the class described, the combination with a chuck adapted to enter a can body and provided with an off-set, of a hollow crimping member surrounding said chuck and provided with a corresponding off-set, said crimping member being adapted to be moved into eccentric relation to said chuck, and a beveled spring actuated ring interposed between said chuck and crimping member for centering the latter.

5. In a device of the class described, the combination with a chuck adapted to enter a can and provided with an off-set, of a hollow crimping member surrounding said chuck and provided with a corresponding off-set, a flange on said crimping member overlapping a shoulder on said chuck, a beveled ring cooperating with said flange to center the crimping member, a threaded backing member on the chuck, and yielding means between the backing member and ring.

In testimony whereof, I have hereunto set my hand and affixed my seal.

CHESLEY T. SMALL. [L.S.]
